[57] CLAIM

The ornamental design for a golf ball display rack, as shown and described.

DESCRIPTION

FIG. 1 is a top plan view of a golf ball display rack showing my new design;

FIG. 2 is a front elevational view thereof;

FIG. 3 is a left side elevational view thereof, the right side elevational view being a mirror image thereof;

FIG. 4 is a bottom plan view thereof;

FIG. 5 is rear elevational view thereof; and,

FIG. 6 is a perspective view thereof.

The broken lines of the golf balls and hanging hook are shown for illustrative purposes only and form no part of the claim.
